UNITED STATES PATENT OFFICE.

ELMER H. WRIGHT, OF CHICAGO, ILLINOIS.

ELECTRICAL-GROUNDING DEVICE.

Application filed May 9, 1927. Serial No. 139,252.

This invention relates to grounding devices for electrical circuits and more particularly to grounding devices for connecting ground wires of electrical circuits and 5 their conduits or metallic sheathings with water pipe lines.

The main objects of this invention are to provide a grounding device having improved means for connecting ground wires 10 of electrical circuits; to provide an improved form of grounding device wherein the ground wire connection is protected from accidental displacement and injury; to provide an improved form of grounding device 15 wherein the unauthorized tampering with the ground wire connection is virtually prevented; to provide an improved form of grounding device wherein the ground wire connection is concealed within the device yet 20 it may be readily secured in installation; and to provide an improved form of grounding device wherein the ground wire connection is of sufficient metal to adequately handle the electrical load at all times.

25 An illustrative embodiment of the invention is shown in the accompanying drawings wherein:

Figure 1 is a perspective view of the device in a water pipe line.

30 Fig. 2 is a top plan view of the grounding device per se, partly in section to better show the means for connecting the ground wire to the grounding terminal.

35 Fig. 3 is sectional view thereof taken on line 3—3 of Figure 2, a portion thereof being broken away.

As is well known in the electrical wiring art, a water pipe gives the best and most satisfactory ground connection and heretofore in the art, clamps, usually in the form 40 of straps which surround water pipes, have been widely used for securing such ground connection. This form of connection has not proven satisfactory, due to the fact that 45 very often the paint, dirt or grease has not been thoroughly removed from the pipe before placing the band around it, and, therefore, a good electrical connection to the pipe has not been secured. Very often the connection 50 has been so imperfect as to cause arcing and sparking between the clamping and the pipe. Such arcing will soon burn the clamping band to such an extent that it is materially weakened and very often crystallizes and breaks.

In the present invention all the advantages 60 of a water line ground connection have been secured without any of the disadvantages heretofore encountered, due to the fact that a permanent, positive, tight connection with the water pipe is had at all times.

In the construction shown in the drawings 65 the improved device is illustrated in use in the usual water line and meter assembly. This assembly comprises an inlet pipe 1 communicating with the water main (not shown), a manually operable water valve 2 connected to the inlet pipe 1 by an elbow coupling 3, a water meter 4, a service pipe 5 connected therewith by an elbow coupling 6, nipple 7, and a union 8.

A ground wire 9 of the electrical circuit is carried by a bent conduit 10.

The grounding device per se comprises a blind pipe fitting 13 which may be connected 75 with the leg end 14 of a pipe T having head ends 15 which are internally screw threaded for insertion in and connection with the water pipe line between the valve 2 and the water meter 4. One end of the blind fitting 13, which is shown as a reducing 80 coupling, is internally screw-threaded for connection with the ground wire conduit 10.

The end of the blind fitting 13 that is connected with the leg end of the pipe T is 85 plugged with any suitable electrical conducting medium such as the integrally cast mass 17. The medium 17 carries a screw seating binding post or electric wiring terminal 18. The fitting 13 has an opening 19 therein, 90 disposed above the binding post for providing access thereto and is also provided with an externally screw-threaded flanged collar 20. A sleeve 21 having an open end is internally screw-threaded for connection with the externally screw-threaded collar 20. The other end of the sleeve is partially 95 closed but is provided with an aperture for permitting the conduit 10 to pass therethrough for connection with the fitting 13.

In installation of the grounding device, 100 the head ends of the pipe T are inserted in and connected with the water pipe line preferably between the valve and the meter. The blind fitting is next screwed to the leg end 105 of the pipe T, the conduit carrying the ground wire is passed through the sleeve and screwed to the blind fitting, the ground wire drawn into the conduit and secured to the binding post or terminal, and the sleeve is 110

then screwed to the externally screw-threaded flanged collar of the blind fitting.

It will thus be seen that the ground wire connection is protected from accidental displacement and that the tampering therewith by unauthorized persons is virtually prevented. The ground wire connection is thus concealed within the grounding device, yet it may be readily secured in installation and the connection is such that the electrical load may be adequately handled at all times.

While but one specific embodiment of this invention has been herein shown and described, it will be understood that numerous details of the construction shown may be altered or omitted without departing from the spirit of this invention as defined by the following claims.

I claim:

- 20 1. A grounding device for connection with the ground conductor of an electrical circuit, comprising threaded closure means for a standard aperture in a grounded pipe system, and means within said closure means 25 for attaching a ground conductor thereto and a removable sleeve on said closure means for protecting said attaching means.
2. A grounding device for connection with the ground conductor of an electrical circuit, comprising threaded closure means for a standard aperture in a pipe system, said closure means having communicative openings therein, means within one opening for securing a ground conductor to said closure means, a sleeve for closing said aperture, and means extending into the other aperture for protecting said conductor.
3. In combination, a grounded pipe system having a threaded aperture therein, a closure 40 means for said aperture having a threaded

end for engagement with the threaded aperture of said grounded pipe system and being threaded at the opposite end for engagement with the threaded end of a ground wire conduit, said closure means having an opening 45 therein at said opposite end, and means within said opening for securing a ground conductor to said closure means.

4. In combination, a grounded pipe system having a threaded aperture therein, a closure 50 means for said aperture having a threaded end for engagement with the threaded aperture of said grounded pipe system and having an opening extending from the opposite end through one side of said closure means, means within said opening for securing a ground conductor to said closure means, and a sleeve fitting over said closure means and closing the opening at the side of said closure 55 means.

5. In combination, a grounded pipe system having a standard aperture therein, closure means for said aperture comprising a fitting, a conductor electrically connected to the interior of said fitting, and a pipe communicative 60 with the interior of said fitting and enclosing said conductor.

6. In combination, a grounded pipe system having a standard aperture therein, closure means for said aperture comprising a fitting, 65 having a recess and a communicative aperture therein, a ground wire terminal in said recess, a conductor extending through the aperture of said fitting, and electrically connected to said terminal, and a pipe extending 70 into said aperture and enclosing said conductor.

Signed at Chicago this 4th day of May 1927.

ELMER H. WRIGHT.
